FUEL INJECTION SYSTEM FOR INTERNAL COMBUSTION ENGINES

George Stephen Kammer, High Austby, Middleton, near Ilkley, England

Application June 5, 1940, Serial No. 338,998
In Germany March 10, 1939

5 Claims. (Cl. 103—41)

The invention relates to fuel injection systems for internal combustion engines.

It is an object of the invention to provide entirely hydraulic actuation of the injection valves, utilising the fuel itself as hydraulic pressure medium.

It is a further object of the invention to adjust the oil pressure in an accumulator for such valves by automatic means in dependence on the speed of the engine.

Another object of the invention is to provide in a hydraulic accumulator automatic unloading means for the pump supplying the accumulator such that the unloading pressure can be varied.

A further object of the invention is to cause the injection nozzles of the engine to open on a drop in hydraulic pressure in a control line thereto and to close again on restoration of the pressure.

Yet another object of the invention is to provide hydraulic control means for the nozzle valves permitting them to remain open for very short periods, such as 1° to 2° of crank angle.

A still further object of the invention is to provide a double seated valve for the said hydraulic control operable by resilient means at predetermined times to drive the valve member on to one seat, the member automatically returning to its other seat under the effect of the hydraulic pressure.

Another object is to provide two or more sets of orifices in the nozzle and to control the supply of fuel thereto in such a manner as to produce a desired stratification of the charge varying in dependence on the engine speed.

With these and other objects in view the invention will be explained in further detail by means of the accompanying drawings, in which

Figure 1 is a diagrammatic assembly drawing of the plant,

Figure 2 is a sectional elevation of the pump and accumulator,

Figure 3 is a partial central section of one form of distributor for a four cylinder engine,

Figure 4 is a section through Figure 3 on the line IV—IV,

Figure 5 is a section through Figure 3 on the line V—V,

Figure 6 is a partial section through an alternative form of distributor,

Figure 7 is a section through one of the resilient cams for the same,

Figure 8 is a perspective view of one of the cam members,

Figure 9 is a sectional elevation of the injection nozzle and valves.

Figure 10 is a portion of Figure 9 on an enlarged scale to show the nozzle and valve construction.

Figure 11 is a developed view of a part of the cap nut securing the washers to the injector body to show the shape of the orifices.

Figure 12 is a section of Figure 10 on the line XII—XII.

Figures 13 to 18 inclusive are diagrams of different cam shapes and corresponding injection curves, and

Figure 19 is a view corresponding to Figure 10 of a modified form of nozzle valve.

Referring first to Figure 1, a hydraulic pump and accumulator are combined in one casing 43. The pump is driven from the lay shaft 42 and is supplied with liquid fuel by the inlet line 45. The accumulator pressure is varied by the action of a governor 46, shown conventionally as of the fly-ball type, on a shaft 47 as will be subsequently explained in detail, and the fuel under pressure is discharged through the line 5 to a distributor 48.

The line 5 is also branched to feed a nozzle valve 49, of which one is provided for each cylinder of the engine. The arrow indicates the connection of the line 5 to the nozzle valves of other cylinders. The nozzle valve is also connected by a control line 7 to the distributor 48.

The function of the distributor is to drop the pressure in the line 7 when fuel injection is to start and to restore the pressure to terminate the injection period. The distributor is driven by the lay shaft 42, which is duplicated in the figure for the sake of clarity. Similarly the governor 46 is duplicated to show the control of injection times to suit different engine speeds and loads.

The foregoing paragraphs set out in broad outline the cooperation of the various parts of the fuel injection system according to the invention. They will facilitate an understanding of the more detailed description now to be given of the various parts of which the system is composed.

The pump and accumulator are shown in Figure 2. Here the lay shaft 42, positively driven in the usual manner from the engine shaft by means not shown, is mounted in the casing 43. The shaft 42 carries an eccentric 50, against which the pump plunger 51 is pressed by a spring 52. The pump cylinder 53 has ports 54 for the inlet of fuel fed from the passage 55 connected

to the inlet line 45. The pump delivers the fuel through a spring loaded non-return valve 56 and a passage 57 to the accumulator space 58.

The accumulator comprises a plunger 59 urged upwards by a spring 60. A groove 61 with oblique edge is provided in the plunger 59 to register with passages 62 and 63 when the accumulator reaches the desired pressure. The passage 62 communicates with the pump pressure space 64 and the passage 63 through the return system of pipes 10 shown in Figure 1 with the fuel inlet passage 55, so that when the accumulator plunger 59 has reached a position corresponding to the desired pressure, the fuel delivered by the pump plunger 51 passes through the passage 62, the groove 61, the passage 63 and the line 10 back to the inlet passage 55.

The shaft 47 is provided with a worm to engage teeth 65 on the plunger 59. The shaft 47 can be rotated in either direction to turn the plunger 59 and so bring the port terminating the passage 62 into register with a narrower or wider part of the groove 61. This adjustment varies the position of the plunger at which unloading of the pump takes place and accordingly also the accumulator pressure maintained. The shaft 47 is actuated by the governor 46 as indicated in Figure 1.

The fuel is delivered through the line 5 to the distributor 48 and to the nozzle valves 49. A preferred form of distributor as shown in Figure 1 at 48 will now be described.

Referring to Figures 3, 4 and 5, the lay shaft 42 duplicated at the right hand side of Figure 1, has a cam disc 31 mounted upon it. The cam disc 31 has a raised portion 32 tapered in the axial direction to vary the timing by axial movement of the disc. A torsion bar 33 is journaled in the distributor casing 34 and has a lateral arm 35 which is adapted to be lifted by the raised portion 32 of the cam disc 31 passing under it. Near the other end of the rod 33 there is another lateral arm 36 projecting in the opposite direction to the arm 35. The arm 36 is in such a position that a twist of the bar 33 will depress a control valve member 37 by the action of the arm on the stem 38 of the valve.

A piece 39 screwed into the casing 34 constitutes an upper seating for the valve and permits communication past the stem 38 of the valve to the space below the valve when the latter is pressed by the arm 36 off its upper seating. The line 5 from the accumulator pressure space 58 (Figure 2) communicates pressure through a port 41 in the lower seating of the valve to the space above when the valve is lifted. The space between the valve seats is in communication as shown with the control line 7 for the nozzle control valve 49 (Figure 1). The total movement of the valve member 37 may be of the order of .01" or less.

In operation the cam disc 31 is rotated by the lay shaft 42 at the appropriate speed, that is at the same speed as the crankshaft in two-stroke engines or at half that speed in four-stroke engines. Oil under pressure is admitted through the line 5 and port 41, holding the valve 37 against its upper seat 39. The oil pressure is thus communicated by the connection 7 to the nozzle control valve 49, keeping it normally closed.

When the raised part 32 of the disc 31 comes under the arm 35, the latter is lifted and the bar 33 is rotated a little, moving the arm 36 downwards. The arm 36 presses on the stem 38 of the valve member 37 and pushes the valve member

on to its lower seating. The cam rise 32 is higher than is required merely to move the valve member 37 from one position to the other, so that the bar 33 is subjected to elastic deformation under the torsion applied. As a result the valve member 37 is held down on to its lower seating with a sufficient force to keep it there against the hydraulic pressure but not with undue rigidity.

In the position now assumed by the valve the pressure supply from the line 5 is cut off from the control line 7, and this line is put into communication with the space 44 inside the casing 34. The seepage of oil returning through the line 7 due to the relief of pressure is discharged from the space 44 by the return lead 10, of which the end is indicated in Figure 3, to the fuel supply.

After the cam rise 32 has passed the arm 35 the pressure in the line 5 lifts the valve member 37 and presses it on to its upper seat 39, returning the bar 33 to its original position as shown in Figure 3. The line 7 comes under pressure again and causes the nozzle control valve 49 to close.

With a multi-cylinder engine one casing 34 with valve 37 and torsion bar 33 is provided for each cylinder, the several casings being arranged in the distributor 48 radially about the axis of the lay shaft 42, so that one raised part 32 actuates the different valves 37 in correct sequence. The line 5 is branched to the different valves, and similarly the line 10 is branched to the several casings 34. The lines 7 are kept separate, each one leading to its associated nozzle control valve.

Figure 4 shows another valve 37 and its associated parts at 90° from the one described in detail, while Figure 5 shows the four operating rods 33 for a four cylinder engine.

It will be noted that in the distributor construction disclosed there are no closely fitted parts or members liable to seizure or breakage nor are there any springs. The construction is simple and cheap, even including the grinding and fitting of the valve member and seatings, which involve no special features.

It may be found desirable however in some cases to use a spring in place of the torsion bar, and this is shown in Figures 6, 7 and 8, which will now be described.

Figure 6 shows two valves and cams, but only one will be described at first. The valve itself and its connections are as already described in connection with Figure 3, the valve being held normally on its lower seating by the oil pressure in the line 5. The valve stem 38 projects through a gland 18, so that the valve can be pressed on to its upper seating by pressure applied to the stem 38.

A resilient cam 20 can pass under the valve stem 38 and lift the valve 37 through the intermediary of a ball 22, driving the valve on to its upper seating and depriving the line 7 of oil pressure, which then passes away through the lead 10 as before.

The resilient cam 20 is housed in a drum 26, which can be slid axially by means of the governor 46 of Figure 1, in which the connection is indicated conventionally as a bell crank lever.

Figures 7 and 8 show the resilient cam and its arrangement in the drum 26. The cam 20 possesses a longitudinal extension or back plate 28 and is held against the corresponding groove in the drum 26 by a spring 27. The spring 27 is stronger than the maximum hydraulic pressure exerted on the valve 37. When, therefore, the

cam 20 passes under the stem 38, the valve will be raised, and when already on its upper seating, the spring 27 will be compressed. Pressure is thus released from the line 7 just as in the case of the distributor of Figure 3.

Figure 9 shows a cross-section of a twin needle injection valve 49 in place in the cylinder. Parts of the cylinder body as shown at 23, 23 and of the cylinder head at 24, while 25 denotes the crown of the piston at its upper dead centre position. In the injection valve two nozzle needle valves 1 are incorporated in the injector body 2. The hollow pistons 3 are each located in a bore 4 coaxial with the respective needle valve and are of larger diameter than the needle valves themselves. The fuel-feed line 5 is connected to the space 6 around both needles, so that this space is held under constant fuel pressure tending to open the needle valves 1 by differential hydraulic action. To keep the valves in the closed position fuel is admitted from the distributor 48 to the bores 4 by the lines 7. Seepage fuel leaves the injector by a channel 8 connected to the spaces 9 and is taken back to the fuel supply by the line 10.

The actual nozzle is better seen in Figure 10. Therein only one needle valve 1 is shown, which has its seating in the injector body 2. The needle is shown in the closed position. Fuel enters through line 5 into space 6. When the needle valve is lifted, the fuel can also enter the bore 11 and consequently the grooves 12 and the circular groove 12a above or in the washer 13. The washer 13 and also the lower surface of the injector body 2 are machined flat, and the washer 13 has an annular recess 14 coacting with the grooves 12. A further washer 15 abuts against the washer 13 and also has an annular recess 17. Of course more washers may follow. The washer 15 is conical near its edge in the form shown, but of course it may be plane, if necessary.

The washers are secured and pressed together and against the injector body 2 by means of a cap nut 16. Figure 11 shows part of the cap nut 16 as a developed views of its cylindrical surface, having orifices at the level where the washers join, exposing annular recesses between them. If the cap nut is made to fit tightly around the washers, the oil under pressure entering the grooves 12 and 12a and the recesses 14 and 17 can only enter the engine cylinder through the portions of the recesses 14 and 17 facing the orifices in the cap nut 16, while the rest of their circumference is inactive.

Figure 12 shows the arrangement of the grooves and oil leads in the case of two washers, each recess 14 and 17 being fed through a duct 11 from its associated needle valve independently of the other.

Reverting to Figure 6, a second cam 20 and valve 37 are shown. The two valves 37 are connected through separate control lines 7 to the two needle valves of Figure 9, so that the timing of injection may be made different for the two sets of orifices 14 and 17. Of course a third valve with cam and needle valve could be added, and so on, the extra orifices being provided by a further washer. The valves 37 for the other cylinders are appropriately spaced around the cam drums 26 as in the case of the distributor of Figure 3.

The distributor drum 26 is rotated at a speed suitable for the engine in question, that is at crankshaft speed in two-stroke engines, and half this speed in four-stroke engines, and the cams

20 engage the corresponding control valves 37 of the different cylinders in succession and raise them. Thus each time a valve 37 is lifted the pressure fuel entering it through the lead 5 will be cut off and the pressure in the line 7 connected to the corresponding needle valve piston 3 will drop to the pressure prevailing in the return line 10, and so the needle valve 1 to which that particular lead 7 is connected will be raised by means of hydraulic pressure on the conical part of the needle valve. Thereupon the fuel oil under pressure in lead 5 and space 6 will enter the bore 11, the grooves and the recess 14 or 17 and will be pressed out along the portions of the recess 14 or 17 registering with the orifices in the cap nut 16. This gives a ribbon-shaped fuel spray, and as the depth of the recess can be made extremely small, the gap will produce an extremely fine fuel spray.

When the cam 20 passes the ball 22, the spring 27 will again expand and the valve 37 be pressed on to its lower seating, allowing oil under pressure from lead 5 to enter the pipe 7. Since the area of the piston 3 is much larger than the area of the needle, upon which the same hydraulic pressure is exerted, a firm and quick closing of the valve 1 will occur with a sudden interruption of the fuel supply into the cylinder through the orifices in question.

Although the needles of one injector may be operated simultaneously, advantageous effects are secured by choosing the shape of the cams 20 for different timing. In this way many variations of timing can be obtained. It is possible to alter the gap between the washers, that is the thickness of the spray-ribbon, and both the number and the diameter of the orifices in the cap nut. Thus for example one set might only have 3 orifices of $\frac{1}{100}$ in. diameter, and the other set 12 of say $\frac{1}{64}$ in. diameter, and while the gap height of the former set may be of the order of $\frac{1}{200}$ in. the gap of the latter may be $\frac{1}{1000}$ in.

With the depth and the height of the gap and the diameter of the orifices it is, within certain limits, possible to vary the penetration of the fuel particles. The penetration also depends on the pressure of the fuel and the pressure in the cylinder. This variation can advantageously be used to stratify the charge or to produce locally an over-fat mixture in the following manner.

Suppose the sparking plug of a gasoline injection engine is located peripherally in the cylinder head, or two such plugs are located opposite each other and peripherally, while the injector is located in the centre of the cylinder. Let the injection start at a very early stage of the compression stroke, out of few orifices directed towards the piston, which is on its inward stroke. During the long injection period out of these few orifices coacting with the lower washer a fairly evenly distributed weak mixture is produced in the cylinder. Very shortly before the spark has to ignite, injection out of the second, or upper set of orifices, will start and be performed rapidly to full quantity, while the orifices may be directed toward the sparking plugs, or elsewhere, where they will create an overrich or overfat mixture.

Another example of stratifying the charge is for use in compression-ignition engines. Let the orifices of the lower washer be distributed evenly over the periphery and be of very small cross-section, or they may be of moderate diameter and the gap be extremely fine. A very small quantity of fuel will be evenly distributed in the

combustion space and form an extremely weak mixture.

Once this has been self-ignited, the second set of orifices may come into operation and inject the bulk of the fuel to be consumed in a comparatively short time. There may then be a third set of orifices, injecting fuel after the bulk of combustible has already been fed into the combustion space.

It will be seen that by this method it is possible to vary the amount of fuel fed into the cylinder and thus exert a very close control over the process of pressure rise without losing valuable oxygen merely because the fuel molecules cannot be seized by one single set of injection orifices and at one single speed of fuel supply, whereas the amount of excess air would allow more fuel to be burnt without excessive temperature rise. Further, there is no compromise in the best speed of injection at various instants due to limitation in pressure rise, as the rate of fuel feed can be made to vary as desired during the period of injection.

Figures 13 to 18 show different shapes of cams for operating two injector needle-valves, with corresponding curves of opening times in crank angle of the two sets of orifices plotted against the setting of the cam drum 20 along the lay shaft 42 to show the simultaneous rates of fuel feed through the two sets of orifices.

Figure 13 is a diagram in which the abscissae represent different settings of the cam drum 26 along its driving shaft to suit different loads. The settings are carried out by the governor 46 of Figure 1. The ordinates represent time as measured by crank angle. Figure 14 is a development of the two cams showing their location relative to the balls 22 with injection cut right off. As the cam drum is moved to the left the time of injection passes from A to B and gradually increases for one set of orifices, while the other set remains closed. As the cam drum 26 is moved further along the shaft corresponding to the horizontal line BC, the time of injection remains constant, but the second set of orifices comes into operation as represented by the hatched triangle EFG, injecting a continuously increasing quantity of fuel. The line FG is entirely within the line CD, which means that the time of injection is not increased by the coming into operation of the second set of orifices but only the rate of feed. The second set may be regarded as providing the main supply of fuel, while the first set provides pre-injection and post-injection, but all within a constant period of time measured as crank angle. At high loads the bulk of the fuel is fed in in a comparatively short time and at low loads the quantity of feed can be accurately adjusted by the governor to the operating conditions.

Figure 15 is a diagram similar to Figure 13, but with the difference that at heavy loads the second set of orifices continues injecting after the first. The corresponding cams are shown in Figure 16.

Figures 17 and 18 similarly show another timing arrangement in which the first set of orifices opens at a constant time and closes progressively later up to three-quarter load, and the second set, providing the bulk injection, opens progressively earlier at small loads from no load and closes after the other set at loads greater than about three-quarters.

Of course, all sorts of other combinations including more than two cams and sets of orifices

can be made according to requirements. In many instances it will be advantageous to determine the best combination by experiments on the actual engine.

5 It may sometimes be found convenient to adopt the alternative form of nozzle shown in Figure 19. This shows two needle valves 1 in the injector body 2 with the lead 5 to convey fuel at constant pressure to the space 6 around the needle ends. The operating mechanism for the needle valves is not shown, since it is the same as shown in Figure 9.

The nozzle body 19 is in a single piece and is clamped against the injector body by the cap nut 16. One needle valve when open admits fuel to a passage 21 terminating at the centre of the face and registering with a passage 29 drilled on the axis of the nozzle body 1, which terminates a little short of its outer extremity and communicates with orifices 66 drilled to direct the fuel in the desired direction.

15 The other needle valve communicates with a passage 30, which registers with an annular groove 40 in the upper face of the nozzle body, from which oblique passages 67 feed the fuel to orifices 68. The orifices 66 and 68 are arranged in separate rings on a conical projection 69 of the nozzle body. A gasket 70 between the injector body and the nozzle body prevents leakage between the passages but may be omitted if desired.

25 The modification last described is intended more particularly for cases in which a jet of greater penetrating power is required than can be provided by the nozzle arrangement shown in Figures 9 to 12.

35 It can be seen from the foregoing description that the invention permits a hitherto unknown fineness of control of the pressure and temperature cycles of an engine, and the the excess air quantity in compression ignition engines can be reduced without damage to the engine, so that the output can be raised and the specific consumption slightly improved.

40 45 What I claim is:

1. In a fuel injection arrangement for an internal combustion engine, a charging pump having suction and delivery spaces, a hydraulic accumulator constituted by a plunger movable axially in a pressure space and rotatable on its axis and resilient means pressing on the plunger, a feed connection including a non-return valve between the pump delivery space and the accumulator pressure space, an oblique edged groove on the accumulator plunger being located to establish connection between the delivery and suction spaces of the pump when the resilient means has been compressed by a predetermined amount, and means for rotating the plunger to vary the pressure at which the groove establishes the said connection.

2. In a fuel injection arrangement for an internal combustion engine, a charging pump having suction and delivery spaces, a hydraulic accumulator constituted by a plunger movable axially in a pressure space and rotatable on its axis and resilient means pressing on the plunger, a feed connection including a non-return valve be-

60 65 tween the pump delivery space and the accumulator pressure space, said accumulator plunger having a groove located to establish connection between the delivery and suction spaces of the pump when the resilient means has been compressed by a predetermined amount, said groove at a portion thereof progressively varying in

cross sectional area in a direction about the longitudinal axis thereof, and means for rotating the plunger to vary the pressure at which the groove establishes the said connection.

3. In a fuel injection arrangement for an internal combustion engine, a charging pump having suction and delivery spaces, a hydraulic accumulator constituted by a plunger movable axially in a pressure space and rotatable on its axis and resilient means pressing on the plunger, a 10 feed connection including a non-return valve between the pump delivery space and the accumulator pressure space, an oblique edged groove on the plunger being located to establish connection between the delivery and suction spaces of the 15 pump when the resilient means has been compressed by a predetermined amount, and means for rotating the plunger to vary the pressure at which the groove establishes the said connection.

4. In a fuel injection arrangement for an internal combustion engine, a charging pump having suction and delivery spaces, a hydraulic accumulator constituted by a plunger movable axially in a pressure space and rotatable on its axis, and resilient means pressing on the plunger, a 20 feed connection including a non-return valve between the pump delivery space and the accumu-

lator pressure space, an oblique edged groove on the plunger being located to establish connection between the delivery and suction spaces of the pump when the resilient means has been compressed by a predetermined amount, axially elongated teeth on the plunger, a worm in engagement with the said teeth, and means for rotating the worm to vary the position of the plunger at which the groove establishes connection between the delivery and suction spaces of the pump.

5. In a fuel injection arrangement for an internal combustion engine, a charging pump having suction and delivery spaces, a plunger movable into a pressure space to constitute a hydraulic accumulator, a stiff spring urging the plunger into the pressure space, a connection between the pump delivery space and the accumulator pressure space, a non-return valve in the said connection, an oblique edged groove being provided on the plunger to establish communication at a predetermined pressure between the pump delivery and suction spaces, and means for rotating the plunger on its axis to vary the compression of the spring at which said communication is established.

GEORGE STEPHEN KAMMER.
